V. NAFTALI

2,174,993

METHOD OF MAKING NECKTIES

Filed May 11, 1938

UNITED STATES PATENT OFFICE

2,174,993

METHOD OF MAKING NECKTIES

Valentine Naftali, New York, N. Y., assignor of
one-half to Jesse E. Langsdorf, New York,
N. Y.

Application May 11, 1938, Serial No. 207,275

5 Claims. (Cl. 2—146)

This invention relates to neckties. More particularly, this invention relates to an improved method for making neckties of the four-in-hand type.

One of the objects of this invention is to provide an improved method of stitching four-in-hand necktie fabrics.

Another object of this invention is to provide an improved method of making neckties of the character described which shall comprise relatively few and simple steps, which shall be inexpensive to manufacture and which at the same time shall be highly efficient and practical.

Other objects of this invention will in part be obvious and in part hereinafter pointed out.

In the accompanying drawing, in which is shown one of the various possible embodiments of this invention,

Fig. 1 is an elevational view of a folded necktie fabric illustrating a step of the improved method in accordance with this invention;

Fig. 2 is an enlarged cross-sectional view taken substantially on the line 2—2 of Fig. 1;

Fig. 3 is a plan view of the back of the Fig. 1 form of tie after the same has been reversed;

Fig. 4 is an enlarged cross-sectional view taken substantially on the line 4—4 of Fig. 3;

Fig. 5 is an elevational view similar to Fig. 1 but illustrating a modified form of this invention;

Fig. 6 is an enlarged cross-sectional view taken substantially on the line 6—6 of Fig. 5;

Fig. 7 is a plan view of the back of the Fig. 5 form of tie after the same has been reversed;

Fig. 8 is an enlarged cross-sectional view taken substantially on the line 8—8 of Fig. 7;

Fig. 9 is a view similar to Fig. 1 but showing still another modified form of this invention;

Fig. 10 is an enlarged cross-sectional view taken substantially on the line 10—10 of Fig. 9;

Fig. 11 is a plan view of the back of the tie illustrated in Fig. 9 after the same has been reversed; and

Fig. 12 is an enlarged cross-sectional view taken substantially on the line 12—12 of Fig. 11.

It is well known that it is desirable to stitch neckties so that there will be a certain amount of resilience or freedom of stretch in the completed tie and that such neckties have heretofore been stitched by the slow, cumbersome and expensive process of hand work. It is also well known that neckties have been resiliently stitched by specially designed sewing machines of the type illustrated in the patent to Naftali et al., No. 1,931,447, granted October 17, 1933, for Sewing

machines. As described in the said Naftali pat-

ent, the folded four-in-hand necktie fabric is stitched by a continuous row of stitching which is disposed substantially parallel to the longitudinal axis of the necktie. In accordance with the present invention, there has been devised an improved method of stitching neckties which may be accomplished by the use of any suitable standard type of sewing machine and which, when the tie is completed, gives the appearance of hand work.

Referring now in detail to the drawing, there is illustrated diagrammatically the steps comprising the improved method of making four-in-hand neckties in accordance with this invention.

In Figs. 1 to 4 there is disclosed a necktie fabric 20 cut to any desired shape and design suitable for four-in-hand neckties and which has been folded substantially on its longitudinal axis with the wrong side of the fabric outermost. At spaced intervals along the length of the folded tie fabric 20 there is provided relatively short rows of stitching 21 which pierce through the layers 20a and 20b of the tie fabric and which rows 21 are disposed adjacent the free longitudinal edges thereof and in a direction transverse to said longitudinal edges. After the folded tie fabric has been stitched as described, to form a tubular tie casing, the said casing is reversed, or turned inside out, and then appears as shown in Fig. 3 of the drawing, the tie being pressed or steamed 30 in the customary manner. It is seen that only a portion 21a of a single stitch is visible. There is thus provided a machine made necktie which appears to be hand stitched and which is much more sturdy and is more quickly and uniformly 35 produced.

In Figs. 5 to 8, there is disclosed a modified form of the invention in which the longitudinally folded tie fabric 30 is stitched through the folded layers 30a and 30b at spaced intervals along the 40 length thereof by a sewing machine designed to provide bar stitches 31. When the Fig. 5 form of tie is reversed and pressed it will appear as in Fig. 7.

While in Figs. 1 to 8 this invention is shown as applied to four-in-hand neckties of the type having no lining or the so-called self-lined necktie, i. e., a tie in which a portion of the tie fabric is folded in such manner as to serve as a lining, it is understood that this invention may also be satisfactorily applied to the manufacture of any other type or style of necktie.

In Figs. 9 to 11 there is disclosed still another modified form of this invention in which a separate tie lining member 41 is employed and upon 55

which there is superimposed in predetermined relationship, a folded tie fabric 40, as clearly shown in Figs. 9 and 10. In this form of the invention the rows of stitches 42 similar to the rows of stitches 21 shown in Fig. 1 may be employed, or bar stitches similar to the stitches 31 may be employed. However, it is noted that in the Figs. 9 to 12 form of the invention the stitches are caused to pierce both layers 40a and 40b of the tie fabric as well as the lining 41. When the tie is reversed it will appear as shown in Fig. 11 with the tie lining properly positioned within the tubular fabric casing.

It will be seen from the above and from the accompanying drawing that the inner ends of the transverse rows of stitches in the several forms of the invention or the bar stitches 31 in the form shown in Fig. 5 are variously spaced from the folded edge of the tie in the position shown in Figs. 1, 5 and 9 with the result that when the tie is reversed and a fold is made along the line determined by such inner ends of these rows of stitches, the shape of the tie is also determined.

It will thus be seen that there is provided a method for manufacturing neckties by means of which the several objects of this invention are achieved, and which is well adapted to meet the conditions of practical use.

As various possible embodiments might be made of the above invention, and as various changes might be made in the matter hereinabove set forth, it is to be understood that all matter herein set forth or shown in the accompanying drawing is to be interpreted as illustrative and not in a limiting sense.

Having thus described my invention, I claim as new and desire to secure by Letters Patent:

1. In a method of making neckties, the steps comprising folding a necktie fabric longitudinally with the wrong side outermost to provide a folded longitudinal edge and a pair of free longitudinal edges, stitching together adjacently disposed layers of said folded fabric at a plurality of points spaced from each other along the length of said folded fabric, and disposing said stitching transversely of the longitudinal axis of said folded fabric and spacing said stitching a predetermined and varying distance from the said folded edge thereby determining the shape of the tie, then reversing said sewed folded fabric and creasing one of said fabric layers longitudinally substantially along the ends of said stitching remote from said free edges.

2. In a method of making neckties, the steps comprising folding a necktie fabric longitudinally with the wrong side outermost to provide a folded longitudinal edge and a pair of free longitudinal edges, stitching together adjacently disposed layers of said folded fabric at a plurality of points spaced from each other the length of said folded fabric, and disposing said stitching transversely of the longitudinal axis of said folded fabric, and spacing said stitching from said folded edge a distance substantially equal to the width of the completed necktie then reversing said sewed folded fabric. 5

3. In a method of making neckties, the steps comprising folding a necktie fabric longitudinally with the wrong side outermost to provide a folded longitudinal edge and a pair of free longitudinal edges, stitching together adjacently disposed layers of said folded fabric at a plurality of points spaced from each other along the length of said folded fabric, and disposing said stitching transversely of the longitudinal axis of said folded fabric and spacing said stitching a predetermined distance from the said folded edge, then reversing said sewed folded fabric and creasing one of said fabric layers longitudinally substantially along the ends of said stitching remote from said free edges. 15

4. In a method of making neckties, the steps comprising folding a resilient necktie fabric longitudinally with the wrong side outermost to provide a folded longitudinal edge and a pair of free longitudinal edges, stitching together adjacently disposed layers of said folded fabric at a plurality of spaced points along the length of said folded fabric, arranging said stitching in independent rows transversely of the said length, and spacing said rows of stitching sufficiently remotely from the said folded edge to permit the reversal of the stitched folded fabric, then reversing the same and forming a fold substantially along the inner ends of said stitching. 30

5. As an article of manufacture a necktie comprising a resilient fabric casing having inturned overlapping portions intermediate the front and the back thereof, said overlapping portions being joined by a plurality of independent rows of stitching spaced from each other and disposed transversely of the longitudinal axis of said necktie, said stitching being confined to the overlapping portion. 35

VALENTINE NAFTALI.
